R. H. TUCKER

AIR PUMP FOR DEEP WELLS

Filed Dec. 27, 1923

Patented Mar. 24, 1925.

UNITED STATES PATENT OFFICE.

RALPH H. TUCKER, OF LOS ANGELES, CALIFORNIA.

AIR PUMP FOR DEEP WELLS.

Application filed December 27, 1923. Serial No. 682,851.

To all whom it may concern:

Be it known that I, RALPH H. TUCKER, a citizen of the United States, residing at Los Angeles, in the county of Los Angeles and State of California, have invented new and useful Improvements in Air Pumps for Deep Wells, of which the following is a specification.

My invention relates to air driven pumps for deep wells and consists of the novel features herein shown, described and claimed.

An object of my invention is to make an improved air driven reciprocating pump. Another object is to make a pump of the class described in which all of the apparatus is hung upon an air pipe to be inserted or removed from the oil pipe. Other objects will appear from the specifications and drawings.

Fig. 1 is a vertical central section of a well and a pump embodying the principles of my invention.

Fig. 2 is a horizontal cross section on the line 2—2 of Fig. 1 and looking downwardly. The lower end of the well casing 1 has perforations 2 in the zone from which the liquid is to be drawn and the pump is preferably located in this zone. The pump tube 3 extends downwardly from the top of the ground to a point near where the pump is to be located, a reducing coupling 4 is mounted on the lower end of the tube 3 and the pump cylinder 5 is screwed into the lower end of the coupling 4, said cylinder 5 being a size smaller in cross section than the tube 3 so that the upper end of the cylinder 5 forms a shoulder 6. A beveled supporting seat 7 is formed at the lower end of the cylinder 5 and there is an internal screw thread 8 below the seat so that a supporting pipe might be screwed to the cylinder and extend downwardly. If desired this pipe might be a strainer. The foot valve consists of a ring 9 having a beveled periphery to fit the seat 7 and having an internal screw thread into which the ring 10 fits, said ring having a vertical opening 11 and a beveled seat 12 and the ball 13 fitting upon the seat 12. A spider extends upwardly from the foot valve and consists of four arms 14 and a central hub 15 connecting the upper ends of the arms, the lower ends being formed integral with the ring 9. A pump plunger 16 fits in the cylinder 5 above the spider and has up-

wardly opening valves 17. A piston rod 18 is fixed in the hub 15 and extends upwardly. An air piston cylinder 19 has a reduced lower end 20 screwed through the center of the plunger 16 and forming a sliding bearing upon the piston rod 18. The piston 21 is mounted upon the upper end of the rod 18 in the cylinder 19, a cylinder head 22 is fixed in the cylinder 19 above the piston 21. Outlet check valves 23 lead through the wall of the cylinder 19 near its lower end and discharge upwardly. A hollow stem 24 extends upwardly from the head 22, and an expansive coil spring 25 is mounted around the stem 24 and rests upon the head 22. A spring seat 26 is slidingly mounted upon the stem 24 and fits against the upper end of the spring 25. A chambered spider hub 27 is adapted to receive the screw threaded portion of the spring seat 26 and make a stuffing box around the stem 24. Spokes 28 extend radially from the hub 27 and are formed integral with the ring 29 which slides freely through the pump tube 3 and rests upon the shoulder 6. The hub 27 forms a stop 30 and an air pipe section 31 extends upwardly from the stop, braces 32 connect the pipe section 31 to the ring 29. A head 33 is fixed upon the upper end of the stem 24 in the pipe section 31 and is adapted to engage the stop 30 to hold the stem 24 from pulling out of the hub 27. The air pipe 34 is connected to the upper end of the air pipe section 31 by a coupling 35 and the air pipe extends to the upper end of the well so that by pulling up the air pipe 34 the entire mechanism of the pump may be withdrawn from the cylinder 5 and tube 3 and in like manner the mechanism may be inserted. When sufficient air pressure is sent down the air pipes 34 it will pass through the stem 24 to the cylinder 19 above piston 21, and will raise the cylinder head 22 thereby raising the plunger 16 and raising the column of liquid and drawing in more liquid.

When the cylinder 19 is raised enough for the valves 23 to pass above the piston 21, the air pressure will be released through the valves 23 and discharged upwardly through the liquid thereby lightening the column of liquid and facilitating the flow. When the pressure is released between the piston 21 and head 22, by passing through the valves 23, the plunger 16 will be lowered by gravity and by force of the spring

25 and the liquid will pass upwardly through the valve 17.

A continued supply of air pressure will cause the plunger 16 to reciprocate and 5 force the liquid upwardly through the pump tube 3.

Reducing the lower end of the cylinder 19 enlarges the area which may be used in 10 making the valves 17 and facilitates the connection of the cylinder 19 to the plunger 16 and making the sliding bearing around the piston rod 18. Instead of reciprocating the piston 21 as is usual with the plunger, the piston is held stationary by connecting 15 the rod 18 to the spider and to the foot valve and the cylinder 19 is reciprocated to operate the plunger.

Thus I have produced an air driven reciprocating pump comprising a pump tube, a 20 pump cylinder at the bottom of the pump tube, said cylinder being smaller than the tube and forming an internal shoulder at the junction, a supporting seat at the bottom of the pump cylinder, a foot valve resting 25 upon the seat, a spider extending upwardly from the foot valve, a valved pump plunger in the cylinder above the spider, a piston rod extending upwardly from the spider, a piston cylinder around the piston rod and having a reduced lower end secured 30 to the plunger and forming a sliding bearing around the piston rod, a piston upon the piston rod in the piston cylinder, a head in the piston cylinder above the piston, outlet check valves leading through the wall 35 of the piston cylinder and discharging upwardly, a hollow stem extending upwardly from the cylinder head, an expansive spring upon the stem against the head, a spring seat slidably mounted upon the upper end 40 of the stem against the spring and having an external screw thread, a chambered spider hub into which the spring seat is screwed to form a stuffing box around 45 the stem and to form a stop, an air pipe section extending upwardly from the stop, a head upon the stem above the stop, a spider ring connected to the spider hub and air pipe section to slide in the pump tube and 50 rest upon the shoulder formed by the pump cylinder, an air pipe connected to the air pipe section, so that the entire pump works may be inserted or removed by operating the air pipe, and so that when sufficient air pressure is sent down the air 55 pipe the piston cylinder will be raised until

the outlet valves are above the piston, thus raising the plunger and the liquid on top of the plunger and drawing more liquid through the foot valve, and then the air 60 pressure will escape through the outlet valves and then the piston cylinder and plunger will move downwardly until the air pressure is restored, and the plunger will continue to reciprocate as long as the 65 air pressure is sufficient.

Various changes may be made without departing from the spirit of my invention as claimed.

I claim:

A pump tube, a pump cylinder at the bottom of the pump tube, there being a shoulder at the top of the pump cylinder, a supporting seat at the bottom of the pump cylinder, a foot valve resting upon the seat, 75 a piston rod extending upwardly and rigidly mounted relative to the foot valve, a valved pump plunger in the pump cylinder, a piston cylinder around the piston rod and having a reduced lower end secured through 80 the plunger and forming a sliding bearing around the piston rod, a piston upon the piston rod in the piston cylinder, a head in the piston cylinder above the piston, outlet check valves leading through the wall 85 of the piston cylinder and discharging upwardly, a hollow stem extending upwardly from the cylinder head, an expansive spring upon the stem against the head, a spring seat slidably mounted upon the upper end 90 of the stem against the spring and having an external screw thread, a chambered spider hub into which the spring seat is screwed to form a stuffing box around the stem, said hub forming a stop, an air pipe 95 section extending upwardly from the stop, a head upon the stem above the stop, a spider ring connected to the spider hub and air pipe section to slide in the pump tube and 100 rest upon the shoulder at the upper end 100 of the pump cylinder, and an air pipe connected to the air pipe section, so that the entire mechanism may be made up and attached to the air pipe section and inserted into the pump tube to rest upon the shoulder and the seat and so that the mechanism 105 may be withdrawn by pulling up the air pipe.

In testimony whereof I have signed my name to this specification.

RALPH H. TUCKER.
